UNITED STATES PATENT OFFICE.

ELLEN LINDSEY HARRISON, OF NEW YORK, N. Y.

DESIGN FOR A PINCUSHION.

Application filed April 28, 1928. Serial No. 26,495. Term of patent 14 years.

To all whom it may concern:

Be it known that I, ELLEN LINDSEY HARRISON, a citizen of Great Britain, and a resident of the city of New York, borough of Manhattan, in the county of New York and State of New York, have invented the new, original, and ornamental Design for Pincushion, of which the following is a specification.

Reference is had to the accompanying drawing, forming part thereof, wherein

I claim:

The ornamental design for a pincushion substantially as shown.

Signed at New York, in the county of New York, and State of New York, this 27th day of April, 1928, A. D.

ELLEN LINDSEY HARRISON.
